UNITED STATES PATENT OFFICE.

HENRY J. GAISMAN, OF NEW YORK, N. Y.

DESIGN FOR A WAIST-BELT.

SPECIFICATION forming part of Design No. 29,037, dated July 12, 1898.

Application filed December 1, 1897. Serial No. 660,442. Term of patent 14 years.

To all whom it may concern:

Be it known that I, HENRY J. GAISMAN, a citizen of the United States, residing in New York city, county and State of New York, have invented and produced a new and original Design for Waist-Belts, of which the following is a specification.

My invention relates to a new and original design for waist-belts; and it consists in the configuration of the parts hereinafter described and shown.

Reference is to be had to the accompanying drawings, forming part of the specification, in which—

15 Figure 1 is a perspective view of a waist-belt embodying my invention; and Fig. 2 is a side elevation thereof, the belt being doubled.

The leading feature of my design consists in a waist-belt having two strap-like parts, 20 one of them located at the front and the other at the back, the front part being wider than the back part, the front part being separated and provided with a fastener, the front part also being connected to the back strap by intermediate loop-like fastenings. The upper

and lower edges of the back part C, forming the lateral limits of said part, lie between the upper and lower edges of the front part B.

In the accompanying drawings the letters A and B indicate the straps of the front part 30 of the belt, and C is a back strap. The front part of the belt is separated and provided with a rectangular fastening E. The front straps are wider than the back strap, and at their inner ends said front straps B are bevelled inwardly and are there connected with loop-like fastenings D, that are also connected with the back strap C. The upper and the lower edges of the strap C are parallel throughout and lie between the upper and lower 40 edges of the front part of the belt. The strap C is located on a plane passing through the center of the front straps B.

I claim—

The design for a waist-belt, substantially as 45 shown and described.

II. J. GAISMAN.
